UNITED STATES PATENT OFFICE.

WALTER S. FORBES, OF PORT RICHMOND, NEW YORK.

ANTIRATTLER FOR WINDOWS AND DOORS.

1,405,575.

Specification of Letters Patent. Patented Feb. 7, 1922.

Application filed October 6, 1919. Serial No. 328,937.

To all whom it may concern:

Be it known that I, WALTER S. FORBES, a citizen of the United States, and resident of Port Richmond, Staten Island, State of New York, have invented certain new and useful Improvements in Antirattlers for Windows and Doors, of which the following is a specification.

This invention relates to improvements in anti-rattlers for use on windows and doors to prevent the same from rattling and disturbing the occupants of a building, the principal object of the invention being to provide a device which may be readily attached to a window or a door in such a manner as to provide a cushion between the frame and the moving element which will effectively prevent rattling.

Another object of the invention is to provide a device which is so constructed that it may be easily put in place and will not mar or injure the appearance of the building.

Still another object of the invention resides in the provision of a device which may be constructed so as to not interfere with the sash cord of the usual double-hung window.

With these and other objects in view the invention consists in the novel construction, combination and arrangement of parts which will be fully set forth in the following specification, claimed and illustrated in the accompanying drawings in which:—

Fig. 1 is a fragmentary perspective view of a window showing this anti-rattler attached thereto.

Fig. 2, is an enlarged detail perspective view of the anti-rattler.

Fig. 3, is a sectional view through a portion of the window illustrating a modified form of the anti-rattler applied thereto.

Fig. 4, is a view similar to Fig. 3, showing a still further modification.

Fig. 5, is a top plan view of an anti-rattler showing the same designed to avoid interference with the sash cord of a window and

Fig. 6, is a perspective view of a modified form of anti-rattler which is particularly adapted for use on doors.

Referring to the drawings in detail, the numeral 10 designates a sash frame provided with the usual side rails 11 and glass pane or sash 12. The anti-rattler is designated in its entirety by the numeral 13 and as illustrated in Fig. 2, consists of a substantially

U-shaped yoke 14 provided with the resilient arms 15, the free ends of which are bent inwardly as at 16 and again outwardly as at 17 in order to prevent the ends of said frames from biting into the wood of the side rails 11.

In order to further protect the rails 11, the extreme ends of the arms 15 are rounded as at 18. The yoke 14 is provided with spaced apertures 19 for the reception of attaching screws or nails 20 by means of which the device is secured in place.

In the modified form of the invention illustrated in Fig. 3, the yoke 21 is provided with the arms 22, the free ends of which are curved inwardly as at 23 and received in recesses 24 at the sides of the rails 11. It will thus be seen that the ends of the arms will be completely enclosed and cannot possibly injure the woodwork.

Referring to the construction illustrated in Fig. 4, the yoke 25 is provided with the right angularly extending arms 26 which are curved inwardly as at 27 and formed at their extreme ends with heads 28. These arms are received in the slots 29 of plates 30 which cover the recesses 31 in the side bars 11 of the sash frame.

In this construction of the device it will be obvious that the ends of the arms will be completely enclosed and will be held in place and against accidental withdrawal from the recesses 31 by contact of the heads 28 with the plates 30.

In the construction of any of the devices hereinbefore described, it will be understood that the yoke portions may be provided with inwardly extending U shaped intermediate sections 32 as illustrated in Fig. 5, which will act to avoid interference of the device with the sash cords of double-hung windows.

In utilizing the device on doors, the construction illustrated in Fig. 6 is best suited as the arm 33 formed on the attaching portion 34 may be placed to engage the door frame and when the door is closed obviously the anti-rattler cannot be seen, thereby avoiding marring the appearance of the woodwork. This construction is also adapted to use on windows where the user finds that two spring arms are undesirable and it will be understood that the end of the arm 33 may be constructed in any manner hereinbefore set forth and also that the attaching arm 34 may be constructed to avoid con-

tact with the sash cord of the double-hung window.

While in the foregoing there has been shown and described a preferred embodiment of this invention, it is to be understood that certain minor changes in the details of construction, combination and arrangement of parts may be resorted to without departing from the spirit and scope of the invention as claimed.

What is claimed is:—

1. A device of the class described comprising an attaching yoke, resilient arms at opposite ends thereof, said arms being adapted

to straddle the sash frame of a window and 15 inwardly and outwardly bent portions at the ends of the arms.

2. A device of the class described comprising an attaching yoke, right angularly extending arms at opposite ends thereof, said 20 arms being adapted to straddle the outer edge of a window sash, the side rails of said sash being recessed, inwardly bent portions at the free ends of the arms, heads on the inwardly bent portions and slotted plates 25 closing the recesses and adapted to retain the heads against accidental withdrawal.

WALTER S. FORBES.
